UNITED STATES PATENT OFFICE.

HARRY N. STEINMAN, OF PITTSBURGH, PENNSYLVANIA.

CUTTING-MACHINE FOR TAILORS' SOAP-CHALK.

1,333,740.

Specification of Letters Patent. Patented Mar. 16, 1920.

Application filed October 11, 1917. Serial No. 195,939.

To all whom it may concern:

Be it known that I, HARRY N. STEINMAN, a citizen of the United States, and a resident of the city of Pittsburgh, in the county 5 of Allegheny and State of Pennsylvania, have invented certain new and useful Improvements in Cutting-Machines for Tailors' Soap-Chalk; and I do hereby declare that the following is a full, clear, and exact 10 description of the same, reference being had to the accompanying drawings, and to the numerals of reference marked thereon, which form a part of this specification.

This invention relates to improvements in 15 a machine for cutting tailors' chalk.

Tailors' chalk usually comes in boxes containing a number of pieces of soap chalk which are thin at the edge and increase in thickness to the center. An objection to this 20 chalk is that the thin edge soon wears off and a thick edge is then presented which makes accurate marking difficult.

It is an object of this invention to provide a machine by use of which a tailor may 25 reshape or cut the chalk so that a uniformly thin edge is presented until the entire chalk is used up, excepting of course the finger grip.

It is also an object of this invention to 30 provide a machine of the class specified by means of which tailors' chalk may be reduced to a uniform thickness and to provide a machine cheap to construct and simple in operation.

35 The invention (in a preferred form) is illustrated in the drawings and hereinafter more fully described.

On the drawings:

Figure 1 is a side elevation of a machine 40 embodying my invention.

Fig. 2 is an end elevation thereof.

Fig. 3 is a top plan view with the top plate omitted.

Fig. 4 is an enlarged fragmentary view of 45 the cutting mechanism.

Fig. 5 is a longitudinal vertical section of the machine.

Fig. 6 is a sectional detail illustrating a part of the gearing mechanism.

50 Fig. 7 is a view partly in section and with parts omitted illustrating the carriage for the chalk.

Fig. 8 is a view of one of the cutters.

Fig. 9 is a plan view of the finished chalk.

55 As shown on the drawings:

1, indicates a table, bench or shelf to

which the machine is attached. Said machine comprises a frame consisting of a plate 2, having transverse bottom and top members 3—4, to which is secured a plate 60 member 5, by means of screws 6. Rigidly secured to the bottom member 3, is a bracket 7, provided with a screw clamp 8, which contacts with a clamping jaw 9, to rigidly attach the machine to the table 1. 65

Grooved ways 10—11 are provided horizontally in said plates 2—5, in which a carriage is adapted to move. Said carriage comprises side members 12—13, movable in said ways which are rigidly connected at 70 each end by means of a cross bar or head 14. Rigidly secured to said cross bars 14, is a rack bar 15, provided with spacing lugs 16, equal in length to the thickness of the middle part of the chalk and a clamping bar 17, 75 is pivotally connected centrally to one of the cross bars 14, and is releasably latched to the other bar 14, by means of a latch 18, engaging a latching pin 19. Also as shown the side members 12 and 13 are provided 80 with a ledge or shoulder 20, on which the ends of the chalk rests while being operated on.

Two shafts 21—22 are journaled to the plates 2—5 one above and one below the 85 carriage on which are secured two sets of cutters 23—24 which are of a width to fit snugly between the members 12—13 and the rack bar 15, and clamping bar 17. These shafts are placed a distance apart, such that 90 the space between the sets of cutter wheels is equal to the thickness that it is desired to have the finished chalk.

The gearing or actuating mechanism is so proportioned that the cutters are revolved 95 at a high rate of speed to effect the cutting and the carriage is actuated at a slow rate of speed.

For this purpose a shaft 25, is journaled in the plates 2—5, below the carriage having 100 an actuating crank or handle 26, secured on one end thereof. A shaft 27, is also journaled in said plates below and parallel with the shaft 25. Rigidly secured or keyed on shaft 25 is a pinion 28, meshing 105 with a gear 29, keyed on shaft 27. A pinion 30 keyed on shaft 27, meshes with a gear 31, loosely journaled on shaft 25, on the hub of which a pinion 32, is rigidly secured which meshes with the rack bar 15, whereby 110 the carriage is advanced or retracted.

Keyed or otherwise rigidly secured on

the end of shaft 25, is a gear 33, which in turn meshes with a pinion 34, on cutter shaft 22, and intermeshing gears 35—36, are rigidly secured on the cutter shafts 21—22 by means of which both are driven simultaneously at the same speed.

Of course the cutters may be of any suitable construction but as shown in Fig. 8, each has a plurality of tangentially directed 10 knives or cutter teeth 37.

The operation is as follows:

The blanks of chalk are placed in the carriage one between each pair of spacing lugs 16, and the clamping bar 17, is hooked 15 in place which firmly retains the chalk in place. Also the width of the clamping bar 17, and rack 15 are equal to the width of the finger grip 38, which is left on the chalk for convenience of handling the chalk.

20 After the chalk is in place, the handle 26, is rotated which advances the carriage slowly to bring the chalk into the field of operation of the cutters which are rapidly rotating, one set acting upwardly and one set downwardly on the chalk passing therebetween to cut the chalk down to the thickness desired. Of course, the central part 25 38, of the chalk between the rack 15 and bar 17, is left uncut to provide a finger grip 30 for using the chalk.

The chalk in its finished state is illustrated in Fig. 9, and it will be seen that both sides 39—40, are thin so that a fine line may be made until the chalk is used up 35 thereby assuring accuracy in marking the cloth.

I have shown a very simple yet efficient machine for cutting tailors' chalk and it is

obvious that many changes may be made and details may be varied through a wide 40 range without departing from the principles of my invention. I therefore do not desire to limit the patent when issued otherwise than necessitated by the prior art.

I claim as my invention:

1. In a device of the class described, a carriage for containing and advancing chalk and substantially cylindrical peripheral cutters above and below and on both sides of the carriage adapted to revolve 50 about axes substantially parallel to the transverse center line of the chalk acting simultaneously to reduce the thickness of the chalk on both sides of the center portion.

2. In a device of the class described, 55 means for containing a piece of chalk, and means for simultaneously reducing the thickness on both sides of the center portion of the chalk and to a substantially uniform extent from each side edge to said center 60 portion.

3. In a device of the class described, a carriage for supporting a piece of chalk, mechanism for advancing said carriage and chalk, and means for reducing the thickness 65 of the chalk at its sides only thus leaving a finger grip at its center and lateral extensions of substantially uniform thickness throughout.

In testimony whereof I have hereunto 70 subscribed my name in the presence of two subscribing witnesses.

HARRY N. STEINMAN.
